BY
James R. Townsend, ATTORNEY.

UNITED STATES PATENT OFFICE.

CHARLES N. HARE, OF LIMA, OHIO.

OCEAN COMPRESSED-AIR POWER.

1,389,445.

Specification of Letters Patent. Patented Aug. 30, 1921.

Application filed November 3, 1920. Serial No. 421,569.

To all whom it may concern:

Be it known that I, CHARLES N. HARE, a citizen of the United States, residing at Lima, in the county of Allen and State of Ohio, (whose temporary residence is Los Angeles, in the county of Los Angeles and State of California,) have invented a new and useful Ocean Compressed-Air Power, of which the following is a specification.

10 This invention relates to appliances for utilizing tide and wave motion of water to operate through compressed air; and the principal object of the invention is to provide an appliance that will be effective and 15 efficient in cheaply compressing air; thereby producing a cheap power for commercial and pleasure purposes.

In other words the appliance is so constructed that tide and wave motion of water 20 is most directly applied to compress air and store it in a storage tank so that afterward the compressed air may be used to actuate an air engine that is connected by any well known means to a motor for producing electrical energy; or the engine can be connected directly by belt and pulleys to a line shaft for driving machinery or pleasure appliances, such as are commonly located at the sea-side beaches.

30 A further object of my invention is to provide an appliance that will be strong and durable and not easily injured by strong tides or heavy ground swells incident to the action of the sea. This feature of the invention is very important as it is well known 35 that appliances heretofore employed for utilizing wave power of the ocean have been easily wrecked or made inoperative by the tremendous smashing and crushing power 40 of the sea in storm action.

In this invention the reciprocating parts are inclosed by a substantial open cage or frame that at the bottom has a firm anchorage in a cement base and the top secured to 45 the pier frame that is effectively supported. This cage permits free action of the water to the reciprocating cylinders but shields these parts from injury by objects carried by the sea.

50 Another object of the invention is to provide an appliance that will be entirely automatic after it is installed in operating posi-

tion in the ocean, so that it will not require an attendant or care-taker to keep it in running order, thereby eliminating operating 55 expenses except those incident to wear and tear.

A feature of the invention is simplicity of construction.

Another feature is shown in the simple 60 means employed for keeping the interior of the reciprocating inner cylinder free from water accumulation.

Another feature of the invention is shown in the novel means employed to support the 65 reciprocating cylinder over an inclined water way so that incoming tide or wave will wedge under the cylinder and force it upward.

Other objects, advantages and features of 70 invention may appear from the accompanying drawings, the subjoined detail description and the appended claims.

The accompanying drawings illustrate the 75 invention in one of its forms.

Figure 1 is a side elevation of the appliance in operation.

Fig. 2 is a section greatly enlarged on line x^2 , Fig. 1, showing a detail of various parts.

Fig. 3 is a fragmental section on line x^3 , 80 Fig. 2 in reduced scale. Parts are omitted for the sake of clearness. The water is shown at the trough in solid lines, and at crest in dotted lines.

Fig. 4 is a fragmental section on line x^4 , 85 Fig. 3, showing a detail of the water channel under the reciprocating cylinder.

Fig. 5 is an enlarged detail of parts above the base in the lower left hand corner of Fig. 3.

The base 1 is firmly anchored in the ocean bed so that its top will be slightly submerged at low tide, a cage 2 has its lower end firmly secured in the base 1 and is preferably formed of T-irons 3, secured together 95 by cross plates 4.

A platform 5 supported by piling 6 has its sea end 7 positioned above and secured to the cage 2.

The uprights 3 are spaced equidistant 100 apart, are positioned an equal radial distance from a common center; and are secured together so that they form an open octagonal case 2.

The upper ends of uprights 3 are secured to platform 5 by plates and bolts well known in the art.

To platform 5 there are secured inclined supports 8 and angle irons 9 to which is secured the upper end of a stationary cylinder 10 which has its upper end inclosed by end plate 11, and its lower end open and held central in cage 4 by the supports 8 and angle irons 9.

A reciprocating cylinder 12 is provided having its exterior surface arranged to form a sliding fit in cylinder 10. That is to say, the outside diameter of cylinder 12 is slightly less than the inside diameter of cylinder 10, so that cylinder 12 can freely move up or down in cylinder 10. The upper end of cylinder 12 is open and its lower end is closed by the end plate 13.

To the lower end and outer wall of cylinder 12 there is secured a flange 14 of a channel ring 15; and the other flange 16 of such channel ring is secured to the lower inner wall of a guide cylinder 17 that is substantially the same length as cylinder 12. The connection of the channel ring 15 to the bottoms of the cylinders 12, and 17 is such as to form a water-tight connection between the parts; and the arrangement is such as to form an annular compartment or cylindrical chamber 18 between the cylinders 12 and 17, to contain liquid for a seal between the stationary cylinder 10 and reciprocating cylinder 12 when the latter is actuated; it being understood of course that the chamber 18 is always sufficiently filled with water or other sealing liquid before the appliance is put in operation and which chamber is automatically kept in a filled condition due to moisture gathering on the stationary cylinder by atmospheric conditions and which moisture flows into the said chamber by gravity.

Secured to the outer wall of cylinder 17 are the guide bars 19 which in practice are preferably T-irons riveted to the cylinder 17 and so positioned that their outer ribs 20 extend radially from the center of cage 4, and their body portions 19 are parallel with uprights 3.

To each of the uprights 3 are secured brackets 21 that have on their free ends friction rollers 22 that are adapted to contact with the outer edges of ribs 20 and hold the cylinder 17 central in its reciprocating movement.

The rollers 22 have flanges 23 that extend slightly over the sides of the ribs 20 and hold the cylinder 17 from rotation on its axis.

Said rollers 22 are spaced apart on each of the uprights 3 so that a number of them from the eight points of support are in contact with the guide bars 19 to hold the cylinder 17 central in its reciprocating move-

ment; and consequently hold the inner or reciprocating cylinder 12 central to the axis of the stationary cylinder 10 so that cylinder 12 can move up or down with minimized frictional contact between its outer wall and the inner wall of cylinder 10.

To strengthen the wall of guide cylinder 17, additionally to guide bars 19, other T-irons 24 are spaced equidistant around the cylinder 17 and are riveted thereto; and additionally binding these T-irons 24 to the cylinder 17 are bridge bars 25 that have their ends properly secured to adjacent guide bars 19, shown in detail in Fig. 2.

The upper end of stationary cylinder 10 is provided with an air inlet valve 26 that opens to admit air to chamber 27 when cylinder 12 descends, and closes as the cylinder moves in the other direction.

An exhaust valve 28 is located in pipe line 29 that connects the chamber 27 with the storage tank 30 which is preferably located on the platform 5; and it is of sufficient size and strength to contain a great volume of compressed air.

Normally the reciprocating tank 12 and guide tank 17 are afloat, but provision is made for limiting their downward movement by oppositely disposed portions of their bottom ends contacting with the top surface of base 1.

Said base 1 has a central channel 31 in its top that forms a clearance between the bottoms of tanks 12, 17 when they are in their lowest position; and this channel is so positioned that the incoming water from the sea will force itself between tank and base to lift the latter upward with great force to compress the air in chamber 27 and drive it into the storage tank 30.

The channel 31 is slightly inclined from the sea end 32 upward toward the land end 33 so that the water will be deflected upward by the contour of the channel to impart its lifting power to the tanks and without diverting the general direction of travel of said water.

Tanks 10, 12, 17 can be of any desired length best suited to obtain a pre-determined air pressure which of course will be governed by the depth of the liquid seal 18; as the deeper this seal is, the greater will be the air pressure in chamber 27 before escaping from the seal; or the safety valve 40 can be set so as to relieve the air pressure from the tank before it becomes high enough to escape by way of the liquid seal. The water seal 18 increases in depth as the reciprocating tanks 12, 17, are forced upward; so that at the highest pressure of air in the tanks,

the seal will be at its greatest depth, and consequently afford a greater resistance to the escape of air from the cylinders. Accumulation of excessive water in tank 12 is prevented by means of pump 33 that is pro-

90

130

vided with the usual casing 34 and valve 35. A suction head 36 is slidably mounted in the casing 34, and is provided with a valve 36' and is secured to a sucker pipe 37 secured to 5 and discharging at the top side of tank 10.

The casing 34 is provided with the usual float valve 38 that closes by gravity and opens when the bottom of tank 12 is flooded with water; and when valve 38 is open the 10 reciprocating movement of tank 12 will automatically actuate the pump 33 to pump water out of the tank.

The storage tank 30 is provided with the drain cock 39 so that it also can be kept free 15 of water, see Fig. 3.

Safety valves 40, 41 are provided for tanks 10 and 30; and the tank 10 is also provided with an air-tight manhole 42.

If desired an air engine 43 can be positioned 20 on platform 5 and connected directly to the valve controlled pipe 44 to the storage tank 30 so that power from the engine can be transmitted to a motor or line shaft; or the pipe 44 can be extended to any point 25 desirable where it can be employed to actuate a motor, an engine; or other compressed air appliance or appliances.

In practice the apparatus is installed 30 where the cylinder 12 will be subject to wave or tide motion; so that intermittently the tank 12 is raised and lowered.

As the cylinder 12 descends, it causes suction 35 in chamber 27 that opens valve 26 and admits air to the chamber; after which, the valve closes. Then the trapped air in chamber 27 is forced outward by the lifting power of the waves acting on cylinder 12; and the compressed air lifts valve 28 in line pipe 29 and enters storage tank 30.

40 The movement of the cylinder 12 is entirely automatic, upward by the lifting power of the waves and downward by gravity.

The size and capacity of the apparatus is 45 unlimited save by limitations incident to the skill and power of men as builders, so that with this invention an unestimated power is available.

I claim:

50 1. In an apparatus of the class described, a base, a cage secured to said base, a stationary cylinder secured to said cage, a reciprocating cylinder mounted in said cage, and telescoping with said stationary cylinder, and 55 means for applying a liquid seal between the reciprocating cylinder and both sides of the stationary cylinder.

2. In an apparatus of the class described, a base, a cage having its lower end secured 60 to said base; a stationary cylinder at the upper end of said cage; a reciprocating cylinder mounted in said cage and telescoping with said stationary cylinder; means for applying a liquid seal between the reciprocating cylinder and both sides of the sta- 65

tionary cylinder; and means for holding said reciprocating cylinder from rotation and for guiding it in its reciprocating movement.

3. In an apparatus of the class described, a base having an inclined channel extending 70 across its top, a cage having its lower end secured to said base, a stationary cylinder at the upper end of said cage, a reciprocating cylinder telescoping with said stationary cylinder, means connected with said cage for 75 guiding said reciprocating cylinder; said inclined channel being adapted to direct the force of the water upward against the bottom of said reciprocating cylinder without diverting the general direction of travel of 80 said water.

4. In an apparatus of the class described, a base, a cage having its lower end secured to said base, a stationary cylinder at the upper end of said cage, a reciprocating cylinder mounted in said cage and telescoping with said stationary cylinder; means for applying a liquid seal between the stationary and reciprocating cylinders; and a pump arranged inside said stationary and reciprocating cylinders and actuated by movement of the reciprocating cylinder to pump leakage from the reciprocating cylinder. 85

5. In an apparatus of the class described, a base, a cage having its lower end secured 90 to said base, a stationary cylinder secured at the upper end of said cage and having its axis in alinement with the axis of said cage; a reciprocating cylinder mounted in said cage and having its upper end telescoping 95 and movable within said stationary cylinder; a channel ring secured to the bottom of said reciprocating cylinder; and a guide cylinder secured to said channel ring; said guide cylinder and channel ring being positioned 100 relative to said reciprocating cylinder so that a cylindrical liquid chamber is formed 105 between the guide and reciprocating cylinders.

6. In an apparatus of the class described, a base, a cage having its lower end secured to said base, a stationary cylinder arranged at the upper end of said cage and having its axis in alinement with the axis of said cage; a reciprocating cylinder in said cage 110 and arranged with its upper end telescoping in the lower end of the stationary cylinder; a guide cylinder; a connection between the bottom of said guide cylinder and said reciprocating cylinder; said connection spacing said guide and reciprocating cylinders apart so as to form a cylindrical liquid seal chamber between them; guides on said guide cylinder; and rollers mounted on said cage and adapted to contact with 115 said guides. 120

7. In an apparatus of the class described, a base, a cage having its lower end secured to said base, a platform connected to the upper end of said cage, a stationary cylinder 130

- 4
- secured to the platform and having an open lower and closed upper end and positioned so that its axis is perpendicular to said platform; and a reciprocating cylinder in axial alignment with said stationary cylinder said reciprocating cylinder being movable within the stationary cylinder for the purpose of compressing air, and said base having an inclined channel extending across its top 5 so as to force water upwardly against said reciprocating cylinder and without diverting the general direction of travel of said water.
8. In an apparatus of the class described; 15 a base; a cage having its lower end secured to said base; a platform connected to the upper end of said cage; a stationary cylinder secured to and positioned perpendicular to said platform, and having a lower end 20 open and suspended in said cage, and also having a closed upper end extending above said platform; a reciprocating cylinder positioned central to the axis of said cage and stationary cylinder, said reciprocating cylinder having a closed bottom end and 25 an open top end fitted and movable in the stationary cylinder; a channel ring secured to the reciprocating cylinder; a guide cylinder secured to said channel ring; and a 30 roller connection between said guide cylinder and said cage.
9. In an apparatus of the class described; a base; a cage having its lower end secured to said base; a platform connected to the upper end of said cage; a stationary cylinder secured to and positioned perpendicular to said platform and having its axis central to the axis of said cage; a reciprocating cylinder with its upper end telescoping the 35 lower end of the stationary cylinder; a channel ring secured to the lower end of the reciprocating cylinder; a guide cylinder secured to said channel ring said guide cylinder positioned relative to the reciprocating cylinder so that an annular cylindrical 40 water-tight chamber is formed between them, and means for guiding the guide cylinder.
10. In an apparatus of the class described; 45 a base; a cage having its lower end secured to said base; a platform connected to the upper end of said cage; a stationary cylinder secured to and positioned perpendicular to said platform and having its axis central to the axis of said cage; a reciprocating cylinder in said cage, said reciprocating cylinder telescoping the stationary cylinder; a guide cylinder; a connection between the bottoms of said guide cylinder 50 and the reciprocating cylinder, said connection holding said guide cylinder and reciprocating cylinders apart so as to form an annular cylindrical chamber between them adapted to contain water; guides on said 55 guide cylinder; brackets on said cage; and
- anti-friction rollers on said brackets, said anti-friction rollers being adapted to contact with said guide for the purpose specified.
11. In an apparatus of the class described, 70 a base, a cage secured to said base, a stationary cylinder secured to said cage, a reciprocating cylinder mounted in said cage and telescoping with said stationary cylinder, and means secured to and spaced 75 apart from said reciprocating cylinder to form a chamber adapted to contain a liquid and thereby form a seal between said cylinders.
12. In an apparatus of the class described, 80 a base, a cage secured to said base, a stationary cylinder secured to said cage, a reciprocating cylinder mounted in said cage and telescoping with said stationary cylinder, and means secured to said stationary 85 and reciprocating cylinders to remove water therefrom.
13. In an apparatus of the class described, 90 a base, a cage secured to said base, a stationary cylinder secured to said cage, a reciprocating cylinder mounted in said cage and telescoping with said stationary cylinder, and means secured to said stationary 95 and reciprocating cylinders to remove water from the bottom of said reciprocating cylinder and discharge said water at the top of said stationary cylinder.
14. In an apparatus of the class described, 100 a base having an inclined channel on its top surface, a cage secured to said base, air compressing means portions of which are secured to and slidably contacting with said cage, and means for removing water from said slidably contacting portions of such air compressor means.
15. In an apparatus of the class described, 105 a base, a cage secured to said base, air compressing means portions of which are secured to and slidably contacting with said cage, and means for removing water from said slidably contacting portions of such air compressor means.
16. In an apparatus of the class described, 110 a base, a cage secured to said base, air compressing means comprising a stationary cylinder secured to said cage and a reciprocating cylinder telescoping with said stationary cylinder, means for applying a liquid seal between said stationary and reciprocating cylinders, and means for removing excessive 115 water from said reciprocating cylinder.
17. In an apparatus of the class described, 120 a base, a cage having its lower end secured to said base, a stationary cylinder at the upper end of said cage, a reciprocating cylinder having an annular chamber adapted to receive the lower end of said stationary cylinder, a liquid seal in said chamber, and means whereby said reciprocating cylinder 125 is guided to enter the stationary cylinder.

18. In an apparatus of the class described, a base, a cage having its lower end secured to said base, a stationary cylinder at the upper end of said cage, a reciprocating cylinder having an annular chamber adapted to receive the lower end of said stationary cylinder, and a liquid seal in said chamber.
19. In an apparatus of the character described, a base, a cage secured to said base, air compressing means mounted in said cage, and means mounted in said air compressing means for removing water therefrom.
20. In a device of the character described having a stationary and a reciprocating cylinder, another cylinder secured to said reciprocating cylinder so as to form an annular chamber, and a liquid seal in said chamber, said reciprocating cylinder being mounted so as to receive the lower end of said stationary cylinder in said chamber so that the liquid seal therein forms an antifriction joint and a seal between said stationary and reciprocating cylinders.
21. In combination with a base, a cage secured to said base, of a stationary cylinder secured to said cage and having an open lower and closed upper end, a reciprocating cylinder mounted in said cage and having an open upper and closed lower end, means secured to said reciprocating cylinder to form an annular chamber, a liquid seal in said chamber, said stationary cylinder being mounted so that its lower end is submerged in said liquid seal, a casing secured to the closed end of said reciprocating cylinder, a sucker pipe secured to the closed end of said stationary cylinder and telescoping with said casing, and valves in said casing and sucker pipe whereby water may be with-
- drawn from said reciprocating cylinder when the said reciprocating cylinder is actuated.
22. In an apparatus of the character described, a base, a cage secured to said base, a stationary cylinder secured to said cage, a reciprocating cylinder mounted in said cage and telescoping with said stationary cylinder, said reciprocating cylinder being reciprocated by wave motion, means for applying a liquid seal between said cylinders, and means actuated by said reciprocating cylinder to remove water from said reciprocating cylinder.
23. In an apparatus of the character described, a base, a cage secured to said base, a stationary cylinder secured to said cage, a reciprocating cylinder mounted in said cage and telescoping with said stationary cylinder, said reciprocating cylinder being reciprocated by wave motion, and means actuated by said reciprocating cylinder to remove water from said reciprocating cylinder.
24. In combination with a base and a cage secured to said base, of a stationary cylinder secured to said cage, a reciprocating cylinder mounted in said cage and coöperating with said stationary cylinder to compress air, and means secured to said stationary and reciprocating cylinders and actuated by said reciprocating cylinder to remove water from said reciprocating cylinder.
- In testimony whereof I have hereunto set my hand at Los Angeles, California, this 28th day of October, 1920.

CHARLES N. HARE.
